RAY H. FLOYD, OF CHICAGO, ILLINOIS, ASSIGNOR OF FORTY-NINE PER CENT TO
IRVIN W. POWELL AND IRENE E. POWELL

AUTOMATIC SPARK RETARDER

Application filed July 2, 1928. Serial No. 289,674.

This invention relates to devices for automatically retarding the spark on an internal combustion engine, and relates more particularly to motor vehicles, as it is desirable to retard the spark, as in starting the vehicle, in order to avoid any possibility of breakage of the starter.

Generally stated, therefore, the object of the invention is to provide an improved construction and arrangement whereby the operation of the starter of a motor vehicle, or of an internal combustion engine for any other purpose, will automatically adjust the timer of the ignition apparatus to thereby retard the spark and avoid any possibility of breakage of the starter, which breakage is liable to happen, as is well understood, if an attempt is made to start the engine while the spark is advanced.

It is also an object to provide certain details and features of construction and combinations tending to increase the general efficiency and the desirability of an automatic spark retarder of this particular character.

To these and other useful ends, the invention consists in the matters hereinafter set forth and claimed, and shown in the accompanying drawings, in which,—

Fig. 1 is a plan view, partly in horizontal section, of an automatic spark retarder for motor vehicles, embodying the principles of the invention.

Fig. 2 is a diagram of the said apparatus.

As thus illustrated, the invention comprises any ordinary or suitable internal combustion engine 1, such as that on an ordinary motor vehicle, provided with a rotary timer 2 of any ordinary or suitable construction. As is usual, this timer has an arm 3 that is suitably connected by link means 4 with the arm 5 at the lower end of the spark shaft (not shown) in the steering column 6, the upper portion of which latter is shown broken away and omitted for convenience of illustration.

At the upper end of this column, adjacent the steering wheel, as is well known and understood, a spark lever (not shown) is provided for adjusting the timer (by rocking said shaft one way or the other) to advance or retard the spark. A starter pedal 7 is

provided, as is shown in the drawings, which are illustrative of one form of the invention, and to avoid any possibility of breakage of the starter, by back firing, when this pedal is depressed, means are provided for automatically retarding the spark as follows:

A helix or coil 8 is provided, in a brass or other suitable shell 9, and pivoted at one end at 10 to a bracket 11 on the motor. The armature of this electric coil is in the form of a reciprocating rod 12 that is slidable endwise in the tubular guide 13 of said coil. A nut 14 is adjustably mounted on the rod-like armature 12, as shown, and a coiled spring 15 is interposed between this nut and the shoulder 16 of the coil structure, whereby the armature is yieldingly held in normal position. The said armature 12 is swivelly or pivotally connected at 17 with the said link means 4 previously mentioned, whereby energizing of the coil, and consequent reciprocation of the armature 12 toward the pivot 10, will result in adjustment of the timer 2 in a direction to retard the spark. This is preferably accomplished automatically by operation of the starter 7, as shown in Fig. 2 of the drawings, it being observed that when the starter 7 is pressed against the contact point 18 to close the circuit from the battery 19 through the motor 20, a circuit is also completed from said battery through the coil 8, through the ground connections 21 and 22, as well as through the ground connections 21 and 23, thus energizing the coil and causing the armature 12 to automatically adjust the timer in position to retard the spark. When the starter is released, the circuit through the coil 8 is automatically opened, and the spring 15 will return the timer to normal position.

It will be seen, therefore, that the invention provides means for automatically retarding the spark, in starting a motor vehicle, or in starting an internal combustion engine of any suitable character, thereby avoiding the possibility of breakage of the starter, which breakage is liable to occur as the result of back firing when it is attempted to start the engine with the spark in advance position.

It will be understood, of course, that the nut 14 can be adjusted to change the normal position of the armature 12, in order to insure the desired results, if such is necessary or desirable.

It will be seen, therefore, that the electromagnet, the armature core, and the spring, all enclosed in the same casing, constitute a unitary electromagnetic automatic timer actuator which can be easily connected in operative position in an ordinary motor vehicle, the unitary device having only two points of attachment, one at each end thereof. The arrangement shown and described, is illustrative of one method of using the said unitary device, but it is obvious that the device can be coupled in position to automatically control the timer in any suitable or desired manner, without departing from the spirit of the invention.

Without disclaiming anything, and without prejudice to any novelty disclosed, what I claim as my invention is:

1. In a motor vehicle, the combination of a timer controller member, a timer subject to manual control by said member, a starter member, an electromagnet solenoid having an energizing circuit controlled by said starter member, whereby the electromagnet is automatically energized when the starter is energized, an endwise movable armature core for said magnet, means whereby said electromagnet solenoid and core have pivotal support and controlling connection with said timer, and a helical spring for said armature core, forming with said magnet and core a movably supported unit in which the spring and solenoid and core have a common longitudinal axis, whereby to automatically restore said core to normal position in said magnet, after the engine is started, the energizing of said magnet serving to move the timer to retarding position, and said spring serving automatically to advance the timer after the engine is started.

2. An attachment for motor vehicles for automatically retarding the spark timer when the engine starter is operated, comprising a cylindrical electromagnet solenoid provided with an endwise movable armature core, a casing enclosing said magnet and armature, providing a chamber at one end of said magnet, a helical spring in said chamber for automatically restoring said armature to normal position when the magnet is de-energized, said armature having a rigid portion projecting from one end of said casing, said projecting portion having means of support, and the other end of said casing having means of support, whereby said attachment may be connected as a movable link in operative relation to the timer of a motor vehicle, and means whereby the motor vehicle starter is operative to automatically close an energizing circuit through said mag-

net solenoid, in starting the engine, to retard the timer, said spring forming with said magnet and core a movably supported unit in which the spring and solenoid and core have a common longitudinal axis, and the spring being operative to restore said armature to normal position after the engine is started, thereby to advance the timer.

Specification signed this 26th day of June, 1928.
